CLAIM

I claim the ornamental design for a bag, as shown and described.

DESCRIPTION

FIG. 1 is a front isometric view of a first embodiment of a bag;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front isometric view thereof in an open configuration;

FIG. 10 is a detail view of an interior portion as indicated in FIG. 9;

FIG. 11 is a rear isometric view thereof in an open configuration; and,

FIG. 12 is a top isometric view thereof in an open configuration.

The evenly dashed broken lines shown surrounding features without surface shading depict portions of the article and form no part of the claim. The dashed lines shown crossing claimed surfaces of the bag depict claimed stitching. The unevenly dashed broken lines in FIGS. 9 and 10 depict cut lines of enlarged portions and form no part of the claim. The oblique lines in the drawings are meant to represent a highly reflective surface.
